WILLIAM E. BERTRAM, OF BROOKLYN, NEW YORK, ASSIGNOR TO INTERNATIONAL TYPESETTING MACHINE COMPANY, OF NEW YORK, N. Y., A CORPORATION OF NEW YORK.

LINE COMPOSING AND CASTING MACHINE.

1,161,796.

Specification of Letters Patent. Patented Nov. 23, 1915.

Application filed February 6, 1913. Serial No. 746,642.

To all whom it may concern:

Be it known that I, WILLIAM E. BERTRAM, a citizen of the United States, residing at Brooklyn, in the county of Kings and State of New York, have invented new and useful Improvements in Line Composing and Casting Machines, of which the following is a specification.

The present invention relates to improvements in line composing and casting machines and more especially to those of the well known linotype class which employ an elevator commonly called the first elevator which operates to receive a line of assembled 10 matrices and convey them down to a position where the matrices are presented to the mold to effect the casting operation and which subsequent to the casting operation, lifts the line of matrices to an upper level 15 where they are transferred to an elevator which conveys them to the distributing mechanism.

More particularly, the invention relates to machines of this class which are adapted to 20 assemble and cast slugs from matrices bearing characters arranged at different levels thereon, the matrices being assembled at different levels to bring one or the other of the characters thereon into use. It is usual 25 to provide the first elevator with a movable rail to support the matrices assembled at the upper level until after the cast has been made whereupon the rail is retracted to bring all of the matrices to a common level 30 preparatory to distribution of the matrices.

The primary object of the present invention is to provide means for retaining such a rail in operative position until the moment when the matrices are to be brought to a 35 common level, this improvement being particularly adapted for use upon first elevators which are commonly hinged to the frame of the machine and are occasionally swung into an open position to render the 40 line of matrices before the mold accessible, the improvement preventing displacement of the movable matrix-supporting rail accidentally, the retaining means, however, being automatically rendered inoperative at 45 the proper time to permit retraction of the rail.

To this end, the invention consists in certain improvements, and combinations and arrangements of parts, all as will be herein- 50 after more fully described; the novel fea-

tures being pointed out particularly in the claims at the end of the specification.

In the accompanying drawing:—Figure 1 is a front elevation of the upper portion of a first elevator embodying the present invention, the elevator being shown in proximity to the limit of its upward movement; Fig. 2 is a perspective view of the matrix-receiving jaws of the first elevator.

Similar parts are designated by the same reference characters in the several views.

The present invention is applicable generally to elevators of different types and it will be understood that the invention is not limited in this respect. In the present instance the invention is shown in connection with an elevator and related mechanism as disclosed in my co-pending application, Serial No. 730,227, filed November 8, 1912, the elevator shown in that application being 75 adapted to use matrices each bearing two or more characters at different levels thereon and capable of being assembled at different levels in order to present the selected characters to the mold. This elevator as commonly used on machines of the linotype class 80 serves to receive a line of matrices, to lower and support the line of matrices before the mold, and after the cast has been made, to lift the line of matrices to the mechanism 85 which serves to transfer them to the distributing mechanism. The elevator 1 embodies, as shown, a pair of co-operative jaws 2 and 3 which receive and support a line of matrices between them. A rail 4 is provided to support the matrices which are assembled at the upper level, this rail in the construction shown being movable in a direction toward and from the line of matrices whereby it 90 may support the matrices at the upper level 95 when moved inwardly and will release such matrices when retracted or moved outwardly, it serving in the latter instance to bring all the matrices to a common level before they are removed from the elevator. 100

Ribs 5 are provided on the rail in the present instance to guide the same in its movements. In the construction shown, the outward or retracting movement of the rail is effected by a bell-crank lever 6 which is pivoted to the elevator and has one arm thereof engaged with the movable rail, while the other arm 7 thereof is adapted to come against a spring-pressed plunger 8 which latter is fixed to the stationary frame 9. 110

This plunger 8 operates the bell-crank lever 6 to retract the matrix-supporting rail 4 when the elevator approaches the limit of its upward movement. A bar 10 serves to 5 automatically return the matrix-supporting rail 4 to operative position when the elevator begins to descend, this bar having a beveled upper end to act upon the right-hand end of the rail 4.

10 It is customary in machines of this class to mount the elevator in a manner which allows it to be swung open and thus permit the operator to readjust, replace, or otherwise manipulate by hand the line of matrices, the elevator being arranged to swing forwardly with reference to its position as shown in Fig. 1. When the elevator is swung forward, the bar 10 can no longer act on the rail 4 to retain the same in matrix-supporting position. The present invention provides means for preventing the matrix-supporting rail 4 from moving out of its normal position accidentally whether due to the hand of the operator coming in contact with it or the bell-crank lever 6, or from any other cause. Such means in the construction shown embodies a latch 11 which is pivoted to the elevator at 12 and has a hooked end 13 which is adapted to 25 operate with a locking projection 14 on the bell-crank lever 6. Gravity serves to hold the latch normally in locking engagement with the projection 14, thereby preventing retraction of the matrix-supporting rail 4.

30 Means, however, is provided for automatically disengaging the latch immediately before the elevator reaches the limit of its upward movement, the latch being provided in the present instance with a projection 15 which is arranged to be engaged by the beveled end of a stud 16, the latter being fixed to a suitable part of the stationary frame 9. When the elevator has nearly reached the 35 limit of its upward movement, the stud 16 operates upon the projection 15 on the latch, lifting the hooked end thereof from engagement with the projection 14 on the bell-crank lever, thereby unlocking the movable matrix-supporting rail 4, and the further upward 40 movement of the elevator brings the arm 7 of the bell-crank lever into engagement with the plunger 8, the latter then serving to retract the rail 4 and causing the matrices assembled at the upper level to drop to the 45 lower level. When the elevator begins to descend, the projection 15 on the latch is carried away from the stud 16, the latch 11 then reengaging the locking projection 14 and holding the rail 4 in normal matrix-supporting position, this rail being returned 50 to such position by the bar 10 as the elevator begins its descent from its uppermost position. The elevator may be swung out from the main frame of the machine thereafter 55 and the matrix-supporting rail will be locked 60

by the latch and hence cannot be displaced or moved into an inoperative position accidentally.

A portion of the swinging vise frame which carries the elevator is shown and designated 17 in the present instance, 18 designating the handle of one of the devices which locks the vise frame normally in operative position. This swinging vise frame may be of the same construction substantially as that shown in the patents to Ottmar Mergenthaler, Nos. 436,531 and 436,532 granted September 16, 1890, the vise frame in the first-named patent being designated m , the elevator l , the shaft on which the vise frame swings outwardly is designated m^{20} , and the locking handle is designated m^{17} . Detail illustration of these parts is therefore considered unnecessary in the present instance, reference being made to those 85 patents for a disclosure of these parts of the machine.

I claim as my invention:

1. In a machine of the linotype class, in combination with the first elevator, a movable rail for sustaining matrices at an upper level, and means, mounted in said elevator, for locking said rail in operative position except when the elevator is in position to transfer the matrices therefrom. 95

2. In a machine of the linotype class, the combination of the first elevator having a movable rail for supporting matrices at an upper level, and means mounted in said elevator and movable into released position by the movement of the elevator for locking said rail in operative position. 100

3. In a machine of the linotype class, in combination with a first elevator having a movable rail for supporting matrices at an upper level, and a latch mounted in said elevator and operative to lock the rail in matrix-supporting position and releasable automatically by the movement of the elevator. 105

4. In a machine of the linotype class, the combination with a first elevator having a movable rail for supporting matrices at an upper level, of a latch mounted in said elevator and normally locking the rail in operative position except when the elevator is in position to transfer the matrices therefrom. 110

5. In a machine of the linotype class, in combination with the first elevator, a movable rail mounted in said elevator for sustaining matrices at an upper level, a latch mounted in said elevator for positively holding said rail in operative position, and automatic means for disengaging said latch relatively to said rail at a certain period of the movement of the elevator. 120

6. In a machine of the linotype class, in combination with a first elevator having a movable rail for supporting matrices at an upper level, a latch mounted in said elevator and normally locking the rail in operative 130

position, means for automatically releasing the latch when the elevator reaches a predetermined position in its movement, and means operative subsequently to automatically move the rail to an inoperative position.

In testimony whereof I have hereunto set

my hand in presence of two subscribing witnesses.

WILLIAM E. BERTRAM.
